FOUNTAIN TOOTHBRUSH

Charles P. French, Turlock, Calif.

Application June 13, 1939, Serial No. 278,884

2 Claims. (Cl. 15—137)

This invention relates generally to an improvement in brushes, and the invention is particularly directed to an improved fountain brush and especially a fountain tooth brush.

The principal object of the present invention is to provide a fountain tooth brush having a tubular handle adapted to receive a separate paste holding ampule or cartridge; such handle including a manually actuated unit arranged to force a predetermined quantity of paste from the cartridge through a passage in the head of the brush and into the bristles for use.

Another object of the invention is to provide a fountain brush of the type described wherein the manually actuated unit for dispensing the paste includes indicia to indicate the amount of paste fed from the cartridge into the tooth brush bristles.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation, partly in section, of the improved fountain tooth brush.

Figure 2 is an enlarged sectional elevation on line 2—2 of Fig. 1.

Figure 3 is an enlarged cross section on line 3—3 of Fig. 1.

Figure 4 is a longitudinal elevation of one of the separate paste holding cartridges.

Referring now more particularly to the characters of reference on the drawing, the device comprises a tubular handle including separate longitudinal sections 1 and 2 removably threaded together at adjacent ends, as at 3, with their bores in communication with each other. The outer end of handle section 1 is closed as indicated at 4, while the outer end of handle section 2 is reduced somewhat in diameter to a neck 5 which is threaded for the reception of a head 6 having a tapped socket 7 in one end thereof and into which said neck is adapted to be screwed. A paste feed passage 8 extends from the interior of section 2 to the outer end of neck 5 and, when head 6 is in place, registers with a passage 9 in said head leading from the bottom of socket 7 to a point of discharge into the bristles 10 of the tooth brush.

The paste P is carried by a separate ampule or cartridge which comprises a tubular body 11 of

a diameter and configuration to snugly and symmetrically but removably engage in handle section 2. The end of the cartridge which is adapted to be disposed in the end of section 2 adjacent neck 5 is tapered, as is the adjacent portion of the bore in said section, and is formed at one end with a removable tip 12 adapted for removal prior to insertion of the cartridge into the handle section. The body 11 is filled with paste and the other and initially open end is then closed by a plug 13 which is of a diameter so that the plug can be pushed the full length of body 11 and to extrude the paste through said one end after removal of tip 12; the inner end of said plug being tapered to correspond to the taper of the body adjacent the tip end.

A plunger rod 14 is slidably mounted in handle section 1; the plunger 14 being guided by circumferentially spaced, radial ribs 15, while at its other end having a headed pin 16 which projects through and is guided by a slot 17 cut longitudinally in said handle section 1. A scale 18 is marked adjacent the slot. The ribs 15 are of sufficient length and are disposed to engage the rod for substantially the entire length thereof when the rod is retracted.

At the outset headed pin 16 is disposed in the end of the slot adjacent the end 4 of handle section 1, and the plunger is in engagement with the outer end of plug 13 in the cartridge. In order to discharge a quantity of tooth paste into the bristles 10 through passages 8 and 9, the headed pin 16 is urged along the slot in a direction toward the head end of the handle. When this occurs, plug 13 is forced a certain distance into the tubular cartridge causing a certain amount of the paste therein to be pressed or extruded through the tip end and into the passages 8 and 9. By providing the scale marks 18 adjacent slot 17, a user can readily determine the proper amount of movement of the pin 16 and connected plunger to discharge the desired quantity of paste into the bristles. As is obvious, the cartridge when all of the paste has been discharged therefrom, is removed from handle section 2 and a new cartridge inserted.

While the invention is primarily designed for use in connection with tooth brushes, it may be successfully used in shaving brushes or the like.

While paste is described as being the material held by the cartridge and fed into the bristles, a semi-liquid or liquid material may be used instead and in such event the passages 8 and 9 would be substantially reduced in diameter.

From the foregoing description it will be readi-

ly seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I 10 claim as new and useful and desire to secure by Letters Patent is:

1. In a fountain brush including a tubular handle, a head on one end of the handle, bristles on the head, there being a passage through the head between the tubular handle at one end and said bristles, a separate paste filled cartridge disposed in the tubular handle and having one end open and in communication with said passage, the cartridge being substantially one-half the length of the tubular handle, a movable plug in the other end of the cartridge, and manually actuated means to effect movement of said plug toward one end of the cartridge; said means comprising a longitudinally extending centrally disposed plunger rod slidably positioned in the handle beyond the plug, said rod being of relatively small

5 diameter and substantially the same length as the cartridge and adapted to engage and move said plug, a plurality of circumferentially spaced radial ribs supporting and guiding said rod, said ribs being of a length to support the rod for substantially its entire length when said rod is disposed in retracted position, a radial pin fixed on the rod adjacent its outer end, the handle having a longitudinal slot therein between adjacent ones of said ribs and through which slot said pin projects for hand engagement.

2. In a fountain brush having a tubular handle member, a head on one end of the member, bristles on the head; there being a passage through the head to the interior of the member, a paste-filled cartridge in the member open at its inner end to the head end of the passage, and a stopper in its outer end of the cartridge forming a plunger adapted for advance into the cartridge; 15 a tubular handle extension removably secured at one end on the outer end of the member, a plunger rod in the extension to engage the stopper and advance the same, centering and guide means for the rod formed in the extension adjacent said one end thereof, and means to advance the rod on the extension.

CHARLES P. FRENCH.
